UNITED STATES PATENT OFFICE.

CHARLES R. DAELLENBACH, OF ELLWOOD CITY, PENNSYLVANIA, AS-SIGNOR TO DAELLENBACH GAS ENGINE COMPANY, OF PITTSBURG, PENNSYLVANIA.

SPEED-REGULATOR FOR EXPLOSIVE-ENGINES.

SPECIFICATION forming part of Letters Patent No. 783,104, dated February 21, 1905.

Application filed December 16, 1903. Serial No. 184,427.

To all whom it may concern:

Be it known that I, CHARLES R. DAELLENBACH, a citizen of the United States, residing at Ellwood City, in the county of Lawrence 5 and State of Pennsylvania, have invented new and useful Improvements in Speed-Regulators for Explosive-Engines, of which the following is a specification.

My invention pertains to explosive-engines, 10 more particularly explosive-engines of the rear-compression type; and it has for one of its objects to provide simple and efficient means for automatically shutting off the supply of explosive mixture to the explosion-chamber 15 when the engine attains an excessively high rate of speed and for reestablishing said supply when the speed of the engine falls to normal.

Another object of the invention is to provide, in an explosive-engine, a construction 20 whereby the exhaust is utilized to heat a hot tube sufficiently to enable the said tube, in conjunction with high compression, to ignite explosive mixture in the explosion-chamber.

With the foregoing in mind the invention 25 will be fully understood from the following description and claims when taken in connection with the accompanying drawings, forming part of this specification, in which—

Figure 1 is a vertical section illustrating an 30 explosive-engine constituting the preferred embodiment of my invention. Fig. 2 is a detail view, partly in elevation and partly in section, taken at right angles to Fig. 1 and illustrating the mechanism for shutting off the supply of explosive-mixture to the explosion-chamber when an excessively high rate of 35 speed is attained. Fig. 3 is an enlarged detail horizontal section taken through the exhaust-passage and the hot tube therein; and Fig. 4 is a detail perspective view, on an enlarged scale, illustrating the lateral projection 40 on the arm of the cut-off valve.

Similar letters designate corresponding parts in all of the views of the drawings, referring to which—

A is a cylinder divided by a piston B into an explosion-chamber C and a compression-chamber D and having a port E for the ad-

mission of air to the compression-chamber, a passage F intermediate of the compression-chamber and the explosion-chamber for conducting explosive mixture to the latter, a port G, communicating with the passage F and adapted to be connected with a source of gasolene-supply, and an exhaust-passage H, 55 leading from the explosion-chamber.

I is a shaft journaled in the side walls of the compression-chamber and having a crank a disposed in said chamber, J a pitman connecting the piston and the said crank, and K a rolling valve bearing in the cylinder and controlling the passage F. The said valve is provided at one end and outside the cylinder with an arm b, on which is a lateral projection c, having a flat inner side d and a slightly-undescut shoulder e, as best shown in Figs. 1 and 4. The said projection c rests loosely in a slot f of a rod L, which is provided at its lower end with a strap g, receiving an eccentric h, fixed on the shaft I outside of the compression-chamber. In addition to the said slot f the rod L is provided with a lateral projection i, from which extends a threaded rod j, bearing a wing-nut k and a coiled spring l. The said spring l is interposed between the wing-nut k and one arm m of a bell-crank lever M, which arm has an opening for the loose passage of the rod j. From this it follows that the spring l tends to hold the arm m of the bell-crank lever against the projection i on rod L after the manner shown in Fig. 1. The bell-crank lever is pivotally mounted at n on the rod L and is provided on its lower arm p with a weight q.

In the practical operation of my novel engine air is drawn through port E and gasolene through port G into the compression-chamber D on the inward stroke of the piston B, and the mixture is compressed in said chamber on the outward stroke of the piston, so that when the piston assumes the position shown in Fig. 1 the mixture will rush into the explosion-chamber C and displace the products of the previous explosion. On the subsequent inward movement of the piston the mixture will be ignited in the explosion-chamber.

- ber by the means presently described, and the piston will be forced outwardly and the operation described repeated. This operation will continue so long as the engine does not attain 5 an excessively high rate of speed, and incident to the same the spring *l* will act against the gravitation of the weight *q* to hold the end of the lever-arm *m* out of engagement with the shoulder *e* of projection *c* as the rod 10 *L* moves up and down. When, however, the engine attains an undue high rate of speed, the weight *q* will overcome the pressure of the spring *l*, with the result that the end of the lever-arm *m* will be drawn into engagement 15 with the shoulder *e* of projection *c*, so that on the subsequent upward movement of rod *L* the arm *b* of the valve *K* will be moved upwardly and the valve rolled to cut off the supply of explosive mixture to the chamber *C*. 20 The valve will remain in the latter position until the speed of the engine falls to normal, when the spring *l* will overcome the gravitation of the weight *q* and press the lever-arm *m* out of engagement with the shoulder *e* of 25 projection *c*. Subsequent to this the projection *c* will drop to the normal position, (shown in Fig. 1,) thereby opening the valve and re-establishing the supply of explosive mixture to the explosion-chamber. 30 It will be readily appreciated from the foregoing that my novel governor mechanism is simple and inexpensive and at the same time sturdy and reliable in operation; also, that by adjusting the wing-nut *k* the strength of the 35 spring *l* may be increased or diminished to suit different conditions.

N is a hot tube disposed in the exhaust-passage *H* of the engine and designed to be heated by the products of combustion as the 40 same pass from the chamber *C*, and *P* is a passage connecting the interior of the hot tube and the inner portion of the combustion-chamber *C*. In virtue of this construction it will be seen that the tube *N* will be sufficiently 45 heated by the escaping hot products of combustion to enable it, assisted by high compression of the explosive mixture in the chamber *C*, to explode said mixture, thus obviating the necessity of employing a spark or a tube 50 heated by extraneous means.

I have entered into a detailed description of the construction and relative arrangement of the parts embraced in the present and preferred embodiment of my invention in order to impart 55 a full, clear, and exact understanding of the same. I do not desire, however, to be understood as confining myself to such specific construction and relative arrangement of parts, as such changes or modifications may be made 60 in practice as fairly fall within the scope of my invention as claimed.

Having described my invention, what I claim, and desire to secure by Letters Patent, is—

- 65 1. In an explosive-engine, the combination

of an explosion-chamber, a piston movable therein, a crank-shaft connected with the piston and bearing an eccentric, a valve for controlling the supply of explosive mixture to the explosion-chamber; said valve being adapted to normally assume and rest in an open position, and having an arm provided with a lateral projection, a rod having a strap receiving the eccentric on the crank-shaft, and also having means for receiving and guiding it on the 75 projection of the valve-arm, and means for automatically effecting connection between the said rod and the projection on the valve-arm and moving said arm when the engine attains an excessively high rate of speed. 80

2. In an explosive-engine, the combination of an explosion-chamber, a piston movable therein, a crank-shaft connected with the piston and bearing an eccentric, a rolling valve for controlling the supply of explosive mixture to the explosion-chamber; said valve being adapted to normally assume and rest in an open position, and having an arm, and a lateral projection thereon provided with a shoulder, a rod having a strap receiving the eccentric on the crank-shaft, and also having a slot receiving the projection of the valve-arm, a bell-crank lever mounted on the rod, and having an arm arranged to engage the shoulder on the projection of the valve-arm, means for 95 normally retaining said arm of the bell-crank lever in a position to clear the shoulder of said projection, and means on the other arm of the bell-crank lever for overcoming the first-mentioned means and causing the bell-crank lever 100 to close the valve when the engine attains an excessively high rate of speed.

3. In an explosive-engine, the combination of an explosion-chamber, a piston movable therein, a movable rod, a driving connection 105 intermediate of the piston and the said rod, a valve for controlling the supply of explosive mixture to the explosion-chamber; said valve being adapted to normally assume and rest in an open position, and having means for guiding the said rod, and means on the rod for engaging the said guiding means of the valve when the engine attains an excessively high 110 rate of speed, and thereby closing the valve.

4. In an explosive-engine, the combination of an explosion-chamber, a piston movable therein, a movable rod, a driving connection intermediate of the piston and the said rod, a valve for controlling the supply of explosive mixture to the explosion-chamber; said valve 120 being adapted to normally assume and rest in an open position, and having an arm, and means thereon for guiding the rod, and means on the rod for engaging the said means on the valve-arm and thereby closing the valve when 125 the engine attains an excessively high rate of speed.

5. In an explosive-engine, the combination of an explosion-chamber, a piston movable therein, a rod connected with and movable by 130

the piston, a valve for controlling the supply of explosive mixture to the explosion-chamber; said valve being adapted to normally assume and rest in an open position, and having an arm, and a lateral projection thereon provided with a shoulder and arranged to guide the rod, a bell-crank lever fulcrumed on the rod and having an arm adapted to engage the shoulder of the projection on the valve-arm, a spring connected with the rod and tending to

press said arm of the lever away from said projection, and a weight on the other arm of the bell-crank lever.

In testimony whereof I have hereunto set my hand in presence of two subscribing witnesses. 15
